COMBINED DESK SET AND LAMP

Herman Rosten, Brooklyn, N.Y., assignor to Allied
Premium Industries, Inc., Brooklyn, N.Y.

Filed Apr. 11, 1962, Ser. No. 69,666

Term of patent 7 years

(Cl. D74—1)

Fig. 1

FIGURE 1 is a perspective view of a combined desk set and lamp, showing my new design;

FIG. 2 is a top plan view thereof with the broken line disclosure of the pens omitted, the lamp shade omitted and the lamp conduit being shown broken away for convenience of illustration.

The dominant features of my design reside in those portions shown in full lines.

I claim:

The ornamental design for a combined desk set and lamp, as shown and described.
